US00D366244S

United States Patent [19]

Kurokawa et al.

[11] Patent Number: Des. 366,244

[45] Date of Patent: **Jan. 16, 1996

[54] SERVOMOTOR DRIVE CONTROLLER

[75] Inventors: Junichi Kurokawa; Takeshi Majima; Katsuyoshi Nakano; Hiromichi Kawashima, all of Ise, Japan

[73] Assignee: Shinko Electric Co., Ltd., Tokyo, Japan

[**] Term: 14 Years

[21] Appl. No.: 33,128

[22] Filed: Jan. 5, 1995

[30] Foreign Application Priority Data

Jul. 7, 1994 [JP] Japan 6-20217

[52] U.S. Cl. D13/162

[57] CLAIM

The ornamental design for a servomotor drive controller, as shown and described.

DESCRIPTION

FIG. 1 is a perspective view of a servomotor drive controller showing our new design;

FIG. 2 is a front elevation view thereof, showing the article which is 5.5 cm wide, 17.5 cm deep, and 19 cm high;

FIG. 3 is a rear elevation view thereof;

FIG. 4 is a top plan view thereof;

FIG. 5 is a bottom view thereof;

FIG. 6 is a right side elevation view thereof;

FIG. 7 is a left side elevation view thereof;

FIG. 8 is a cross-sectional view taken along line 8—8 in FIG. 4; and,

FIG. 9 is a cross-sectional view taken along line 9—9 in FIG. 4.
